UNITED STATES PATENT OFFICE.

MARION C. PRUITT, OF ATLANTA, GEORGIA.

BLOOD-TRANSFUSION APPARATUS.

Application filed May 25, 1920. Serial No. 384,026.

To all whom it may concern:

Be it known that I, MARION C. PRUITT, a citizen of the United States, residing at Atlanta, in the county of Fulton and State 5 of Georgia, have invented new and useful Improvements in Blood-Transfusion Apparatus, of which the following is a specification.

This invention relates generally to apparatus for the transfusion of blood, but it relates more particularly to a receptacle to be used in the indirect method of blood transfusion as a container for the blood to be transferred.

Ordinarily, in the prevalent method of blood transfusion as carried on between two persons, the transfer is effected by filling a 10 syringe with blood from the donor and injecting it into the recipient, this process being repeated until the desired amount has 15 been transferred. This method is considered disadvantageous, in that the extraction of the blood from the donor must be immediately followed by its injection into the recipient in order to obtain the best results, and, such transfer usually requires the 20 attention of two physicians.

My invention provides a receptacle or container into which the blood extracted from 25 the donor is placed and kept in perfect condition and at the desired temperature for a certain time, so that the completed transfer need not be effected immediately, and thus the operation can be efficiently performed by one physician.

An important object of the invention is to 30 provide a receptacle of the character described, which is simple and practical in construction, and which may be manufactured at a reasonable cost.

Another object of the invention is to provide a neat compact receptacle having means for readily attaching thereto a discharge tube, and a compartment for containing the 35 tubing in coiled form when not in use, a suitable cap being provided for closing the compartment and retaining the coiled tubing therein.

A further object of this invention is the 40 provision of an apparatus for use in connection with the transfusion of blood from one person to another, susceptible of a varied use for intravenous injections of fluids into the body, so designed that the fluid to be transferred may be maintained at a desired 45 temperature; preferably constructed of

glass or like transparent element so that the fluid within the container may be visible, and so graduated that the course of the transfusion may at all times be accurately observed.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a side elevation of a receptacle constructed in accordance with my invention;

Fig. 2 is a vertical sectional view showing the interior construction; and

Fig. 3 is a bottom plan view showing the discharge tube coiled within the compartment provided therefor.

Briefly stated, the receptacle forming the subject matter of my invention comprises a 80 double walled container presenting inner and outer compartments for containing, respectively, the blood to be transferred and a heated fluid, such as hot water, for maintaining the contents of the inner compartment at the proper temperature. Both compartments are provided at the top with inlet 85 openings normally closed by suitable caps. The inner compartment is formed at the bottom with a discharge outlet to receive a 90 discharge tube. In order to accommodate the tube when coiled and not in use a compartment closed by an appropriate cap is 95 formed around the discharge outlet, as clearly shown in Fig. 2 of the drawings.

Referring more particularly to the drawings, the reference numeral 1 designates a cylindrical outer shell provided a slight distance above its lower end with a bottom wall 2 having a central aperture 3, and a depending externally threaded neck 4 surrounding said aperture 3. Rising from the bottom wall 2 and concentrically surrounding the aperture 3 is an inner cylindrical shell 5 spaced from the surrounding shell 1 to effect an intervening annular compartment 6 into which the hot water or other heated fluid may be introduced. As shown, the inner shell 5 is made of such height that the upper end thereof projects upwardly 110 beyond the upper end of the shell 1, and this projecting end is externally threaded as

at 7 to receive the correspondingly threaded cap 8.

The annular compartment 6 is closed at the top by a wall portion 9 which extends between the shell 5, immediately below the threaded portion 7 of said wall, and the upper annular edge of the outer shell 1. The said wall portion 9 is provided with an inlet opening 10 and an outwardly extending neck 11, externally threaded as at 12 to receive thereon a cap 13.

Owing to the location of the bottom wall 2 above the lower end of the shell 1, a compartment 14 is provided beneath said bottom wall into which the discharge neck 4 extends. A suitable discharge tube 15 has one end attached to the neck 4, and when not in use may be coiled about the discharge neck and entirely contained within the compartment 14, and retained in such position by the internally threaded cap 16. The flow of liquid through flexible conduit or tube 15 may be controlled by any suitable regulating means.

In practice, the fluid to be transferred is introduced into the inner shell 5 and sealed therein by cap 8, said cap forming an air tight closure to prevent the formation of air bubbles in the liquid, which are dangerous in intravenous injections. The heating fluid such as hot water for maintaining the contents of the inner compartment at the proper temperature is introduced into the outer compartment 6 through inlet opening 10 and sealed therein by cap 13.

From the foregoing it is apparent that I have designed a fluid transfusion apparatus of great adaptability, eliminating many deficiencies of those now in use, efficient in operation, simple in construction, and inexpensive to manufacture.

Although in the foregoing, certain elements may have been set forth as best adapted to perform the functions allotted to them, nevertheless, it is to be understood that various minor changes as to form, substance, etc., may be resorted to within the scope of the appended claims without departing from or sacrificing any of the principles of this invention.

Having thus described my invention, and without enumerating variations and equiva-

lents, what I desire protected by Letters Patent is as set forth in the following claims:

1. A transfusion receptacle, comprising an outer cylindrical shell provided above the lower end thereof with an apertured bottom wall, and having the said lower end externally threaded to receive thereon a threaded cap, said cap forming in conjunction with the bottom wall an intervening compartment, an inner shell rising from said bottom wall in spaced relation to the outer shell and projecting above the upper end of said outer shell, a closure for the projecting end of said outer shell.

2. A transfusion receptacle, embodying a blood chamber having its bottom formed with an outlet opening and its top open and adapted to be closed with a removable cap, an offset jacket surrounding the blood chamber and forming a sealed compartment adapted to receive a heating agent, the walls of the jacket being extended below the bottom of the blood container and externally threaded to receive a cap, the latter when in position forming a housing for the discharge tubing, and a normally closed inlet port communicating with the sealed compartment to effect its replenishment.

3. A transfusion receptacle of the character described embodying a cylindrical shell having top and bottom walls, the bottom wall being set inwardly from the end of the cylinder to provide a housing, an inner cylindrical shell integral with the said set-in wall and extending longitudinally of the outer shell with its outer end penetrating the opposite or top wall of the outer shell, said inner and outer shells being relatively spaced to provide a compartment therebetween, said top wall presenting an inlet to the said compartment and the said bottom wall presenting an outlet for the said inner shell, a discharge tube connected with the outlet of the said inner shell, and closure means at opposite ends of the shells, one of said closure means being engageable with said housing for confining therein the discharge tube when not in use.

May 22, 1920.

MARION C. PRUITT
